(57) **CLAIM**

The ornamental design for a faceplate for a barbecue hood or similar article, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front perspective view of a faceplate for a barbecue hood or similar article showing our new design, wherein the faceplate is shown attached to the hood of an illustrative barbecue.

FIG. 2 is a front perspective view thereof.

FIG. 3 is a rear perspective view thereof.

FIG. 4 is a left side elevational view thereof.

FIG. 5 is a right side elevational view thereof.

FIG. 6 is a front elevational view thereof.

FIG. 7 is a rear elevational view thereof.

FIG. 8 is a top plan view thereof; and,

FIG. 9 is a bottom plan view thereof.

The broken lines in the drawings are illustrative of environmental structure and form no part of the claimed design.
